UNITED STATES PATENT OFFICE.

OTTO SIEMEN AND JOHANNES HINSCH, OF ST. MARGARETHEN-HOLSTEIN, GERMANY.

ROTARY PUMP.

Application filed October 6, 1923. Serial No. 667,068.

To all whom it may concern:

Be it known that we, OTTO SIEMEN and JOHANNES HINSCH, citizens of the German Republic, residing at St. Margarethen-Holstein, Germany, have invented certain Improvements in Rotary Pumps, of which the following is a specification.

This invention relates to a rotary pump of the centrifugal or centripetal type and in which a single rotor is adapted to work in more than one stage, the pump casing being provided with passages whereby part of the impelled liquid is returned to the rotor for the reception of a fresh impulse.

15 The object of the invention is to arrange the different passages so that air or gases drawn in by the pump together with the liquid can be readily disposed of without affecting the regular function of the pump and so that the pump can be started with a completely open pressure side.

This object is achieved according to the invention by arranging about the rotor space, a spiral, circumferential delivery passage whence a by-pass, of smaller sectional area than the delivery passage, leads back to the rotor space and thence back to the delivery passage, the ports through which the by-pass communicates with the rotor space being arranged on a higher level than the inlet port of the pump so that air entering the rotor pockets will be induced to remain at the base of the latter until it arrives at the by-pass ports where it will be 35 expelled by the liquid forced through the latter.

Fig. 1 of the accompanying drawings represents a transverse section of one form of the pump,

40 Fig. 2, an axial section of the same, taken on the line II—II of Fig. 1, and

Fig. 3, a vertical axial section of a pump of modified construction.

The rotor *c* is fitted into a casing having a suction side *a* and a pressure side *g*. The inlet port *b* is arranged close to the center and extends principally underneath the rotor shaft so that air drawn in together with the liquid will remain at the bottom of the pockets and travel round with the rotor. Arranged circumferentially of the rotor space is a spiral delivery passage *d* which is branched off at *e* into a diffuser passage *f* which is of smaller sectional area than the main delivery passage and which opens into the rotor space through a port

*b*¹ arranged above the horizontal center line of the rotor space. Another diffuser passage *f*² which communicates with the rotor space through a port *d*¹, opens into the delivery passage at *f*, close to the junction between the latter and the pressure pipe. The port *d*¹ is arranged between the port *b*¹ and the center of the rotor space.

Part of the liquid driven through the passage *d* will be diverted at *e* and returned at high velocity through the passage *f*¹ to the rotor space. Here the liquid, which possesses sufficient kinetic energy to overcome the centrifugal effect of the rotor, passes inwards to the port *d*¹ through which it enters the passage *f*² whereby it is led back to the delivery passage. As the liquid flows from the port *b*¹ to the port *d*¹, any air which, as previously described, is carried along with the rotor from the inlet *b*, will be compressed by the liquid and forced into the delivery passage through the diffuser *f*².

In the form shown in Figs. 1 and 2, the ports are situated at the side of the rotor so as to deliver and receive the liquid axially of the latter. The pump will function in the same manner if built as shown in Fig. 3. In this construction the rotor space is annular, the rotor being formed with blades which overhang the center portion *i* of the casing. The ports *b* and *d*¹ are situated in the portion *i* so that the liquid can pass the rotor blades from end to end. In the first stage of this pump, the liquid passes from the center to the circumference while in the second stage it passes inwards on the circumference.

In either of these constructions, the pump allows of being started with open pressure side, and the pump is therefore particularly suitable for remote control or for automatic operation.

We claim:

1. In a rotary pump of the character described, a casing having a rotor space with inlet port, a spiral, circumferential delivery passage, and a by-pass of smaller sectional area than the main delivery passage leading from the latter back to the rotor space and thence back to the delivery passage, the ports through which the by-pass communicates with the rotor space being on a higher level than said inlet port, substantially as and for the purpose set forth.

2. In a rotary pump of the character de-

scribed, a casing having a rotor space, a spiral delivery passage arranged circumferentially relative to the rotor space, an inlet passage opening into the rotor space near and principally under the center thereof, and two diffuser passages of smaller sectional area than the delivery passage communicating with said rotor space through ports arranged above the horizontal center line and at different distances from the center, the diffuser passages being also in communication with the delivery passage so as to divert liquid from the latter into the rotor space through the outermost port and return such diverted liquid to the passage through the innermost port.

3. In a rotary pump of the character described, a casing having an annular rotor

space, a spiral delivery passage arranged circumferentially relative to said rotor space, an inlet passage opening into said rotor space radially outside and principally under the center thereof, and two diffuser passages of smaller sectional area than the delivery passage opening radially into said rotor space from opposite directions and above the horizontal center line of the rotor space, the diffuser passages being arranged so as to divert liquid from the delivery passage into the rotor space through the outermost port and return such diverted liquid through the innermost port to the delivery passage.

OTTO SIEMEN.
JOHANNES HINSCH.
